UNITED STATES PATENT OFFICE

162,726

SUSPENDER SLIDE OR THE LIKE

Edward M. Hawie, Stratford, Conn., assignor to
The Hawie Manufacturing Company, Bridgeport, Conn., a corporation of Connecticut

Application March 16, 1950, Serial No. 8,558

Term of patent 7 years

(Cl. D17—15)

To all whom it may concern:

Be it known that I, Edward M. Hawie, a citizen of the United States, residing in Stratford, in the county of Fairfield and State of Connecticut, have invented a new, original, and ornamental Design for a Suspender Slide or the like, of which the following is a specification, reference being had to the accompanying drawing, forming part thereof, in which

Fig. 1 is a front elevational view of a suspender slide embodying my new design; and

Fig. 2 is a side elevational view thereof.

The dominant feature of my design resides in that portion shown by means of full lines in the drawing.

I claim:

The ornamental design for a suspender slide or the like, substantially as shown and described.

EDWARD M. HAWIE.
